UNITED STATES PATENT OFFICE.

DANIEL ROBERT CAMERON, OF VANCOUVER, BRITISH COLUMBIA, CANADA.

GRAIN-DOOR LATCH.

Application filed March 17, 1924. Serial No. 699,728.

To all whom it may concern:

Be it known that I, DANIEL ROBERT CAMERON, a subject of the King of Great Britain, and a resident of the city of Vancouver, in the Providence of British Columbia, Canada, have invented certain new and useful Improvements in Grain-Door Latches, of which the following is a specification.

My invention relates to improvements in latches for grain doors, and the object of my invention is to provide a latch for the doors of grain cars which is of extremely simple and cheap construction capable of being installed with great facility and maintained at a minimum cost, which is highly practical in use, and is so designed and arranged that it may be opened from the exterior of the car with great ease and convenience and without damage to any part of it, thus enabling a grain door to be used over and over again so that the cost of renewals or repairs is reduced to a minimum.

I attain this object by the construction illustrated in the accompanying drawings in which

Fig. 1 is a fragmentary view in perspective of the inside of a car illustrating the embodiment of my invention therewith.

Fig. 2 is a fragmentary view of a car showing the door in outside elevation.

Fig. 3 is a transverse section on the line 3-3 of Fig. 2.

Fig. 4 is a view looking on the inside of the latching device.

Fig. 5 is a sectional plan view taken through the line 5-5 of Fig. 6.

Fig. 6 is an outside view of the latching device.

Similar figures of reference indicate similar parts throughout the several views.

In the drawings 1 indicates the outside wall of a typical grain car, 2 the doorway, 3 and 4 the vertical standard posts on opposite sides of the doorway, 5 the bottom frame sill, 6 the inner lining of the car, and 7 the floor.

The door consists of two sections, preferably of wood, a comparatively narrow lower section 8 which when in place rests on the bottom sill 5 and a main section 9 the lower edge of which when in place rests on the upper edge of the lower section while its upper edge extends to within a short distance from the top of the doorway 2, leav-

ing an opening 10, as shown in Figs. 1 and 55 2. At one side edge each section 8 and 9 respectively engages in a vertical groove 11 formed in a post 12 secured to the inner lining 6 while at its opposite side edge the main section 9 extends beyond the edge of 60 the doorway and rests against the lining and thus the main section extends completely across the doorway and therefore being wider than the same is prevented from outward dislodgment under grain pressure 65 from the inside by its engagement with the groove 11 on one side and contact with the car wall on the opposite side.

The opposite side edge of the lower section 8 extends into close proximity to the side of the doorway so that being therefore shorter when in place than the width of the doorway it is capable of being swung outwardly under grain pressure from the inside of the car when the latching device associated with it to prevent such outward swinging now to be described is withdrawn from in front of it.

The latching device, which is illustrated more particularly in Figs. 4, 5 and 6 and is indicated generally by the numeral 13, consists of a plate 14 of substantially the same depth as the door section 8 provided with a rack bar 15 and this plate is freely mounted against the inner lining 6 at the side of the doorway opposite to that on which the grooved post 12 is secured and positioned so that when in its inmost position, as herein-after referred to, its outer edge does not project beyond the edge of the doorway but when in its outmost position it extends in front of the door section 8, as shown in Fig. 3. This plate 14 is enclosed by a cover 16 which is secured to the car lining over the plate by bolts 17 and 18 and is flanged inwardly around its edge as at 19 to provide space for the plate 14 and its rack bar 15 to operate in, being provided with stiffening pieces 20 and 21 on its inner face to prevent warping when the bolts 17 and 18 are tightened up. The upper and lower portions of the flange 19, indicated specifically by the numerals 22 and 23, provide guide surfaces on which guide arms 24 and 25, formed integrally on the rear or inner end 95 of the plate 14, as shown in Fig. 4, move during operation of the device while the end portion 26 of the flange 19 acts as a

100

105

stop co-operating with the outer end 27 of the rack bar 15, which is thicker than the plate 14, to limit the outward movement of the plate.

5 28 indicates a toothed segment meshing with the teeth 29 of the bar 15 which segment is secured to a partially rotatable shaft 30 extending through the side of the car and which shaft is provided on its outer 10 end with an operating lever 31, and to act as a guide for the rack bar and maintain it in close mesh with the segment 28 a bolt 32 is provided which extends through the side of the car and the cover 16, on which 15 bolt the upper edge of the rack bar bears, as shown in Fig. 4.

The plate 14 is provided on its inside face adjacent its outer edge with a tongue 33 which is substantially the same length 20 as the width of the plate and the cover 16 is pressed out to form a hood 34 which covers the tongue when the plate and tongue are in the inmost position, the cover being slotted as at 35 to permit longitudinal movement 25 of the tongue when the plate is operated, this slot being necessary as it is preferable to keep the flange 26 unbroken, to prevent the grain from entering between the cover and the plate. The hood is also 30 made a good fit over the tongue so as to prevent the grain from entering between them.

A vertical post 36 is secured to the lining 6 a short distance in from the edge of the doorway, above the locking device, as shown in Fig. 1, to prevent lateral movement of the main section 9, and on this post are preferably pivoted clips 37 which may be swung around to engage the back of the section when in place. The lower corner of 40 the main section, indicated by the letter A in Fig. 1, rests when assembled on the locking device cover 16, as shown, and on its inner side at its lower edge there is secured a strip 38 which projects below it and covers 45 the joint between the main section and the lower section 8, as shown in Fig. 1. A rigidly secured staple 39 is provided which projects through a slot in the operating lever 31 when the plate 14 is in its outermost position so that by means of a suitable pin 40 passed through the staple on the outside of the lever the latter is held against inadvertent displacement.

The manner in which the invention operates and its utility will be apparent, reference being had particularly to Figs. 4, 5, and 6 and to Fig. 1, in which latter view the latching device is shown assembled and secured to the car wall. It will be seen 55 that if the lower section 8 be placed in position with one end resting in the groove 11 of the post 12 and the plate 14 projected from the cover 16 by the operation of the lever 31 this section is then held against outward movement, and that the main section

9 when placed in position with one end engaging the groove 11 and its opposite end bearing on the inside wall of the car is also maintained against outward movement so that with the sections in position 70 the door is firmly closed against discharge of grain from the inside of the car. To open the door all that is necessary is to operate the lever 31 to retract the plate 14 from in front of the lower section 8 whereupon the grain pressure will swing it outwardly and the grain will flow through the opening under the main section, permitting 75 partial discharge, and enabling both the sections to be removed so that the entire 80 grain load may be discharged in the usual manner through the fully open doorway.

This result is obtained without breakage 85 of the door or damage thereto so that the door sections are available for use with subsequent loads with a minimum of expense for renewals or repairs.

From the foregoing it will be seen that I have devised a simple, practical, and efficient latch for a grain door which is cheap to manufacture and install, economical to maintain, and which is of great utility and convenience.

What I claim as my invention is:

1. A grain door latch, comprising a latch plate extending throughout the greater part of the depth of the door, and slidably mounted on the inner side of the car adjacent the doorway and susceptible of having its edge projected beyond the edge of the doorway or retracted clear thereof, and means for operating the plate from the outer side of the car by means of a lever, the weight of which tends to hold the plate in the retracted position.

2. A grain door latch, comprising a latch plate extending substantially the depth of the door and slidably mounted on the inner side of the car and susceptible of having its edge projected beyond that of the doorway or retracted within that edge, said plate having rack teeth about the mid-depth of the plate, disposed in the line of movement, a toothed segment meshing with the rack, a shaft rotatably mounted in the side of the car through which it passes to the outer side, on the inner end of which shaft the toothed segment is secured, and a lever secured on the outer end of the shaft the weight of which lever tends to hold the latch plate in the retracted position clear of the doorway.

3. A grain door latch, comprising a latch plate of a depth substantially the same as that of the door, said plate slidably mounted on the inner side of the car and susceptible of having its edge projected beyond the edge of the doorway or retracted clear thereof, said plate having rack teeth about its mid-depth and disposed in

the line of movement, a toothed segment meshing with the teeth of the rack, a shaft rotatably mounted in the side of the car and projecting through the outer side, a lever secured on the outer end of said shaft the weight of which lever tends to hold the latch plate in the retracted position clear of the doorway, and a cover secured to the inner wall of the car and forming therewith a grain-tight enclosure for the latch plate and its mechanism.

Dated at Vancouver, B. C., this 16th day of January, 1924.

DANIEL ROBERT CAMERON.
